UNITED STATES PATENT OFFICE

EDWIN L. POWELL, OF WASHINGTON, DISTRICT OF COLUMBIA, ASSIGNOR, BY MESNE ASSIGNMENTS, TO FEDERAL TELEGRAPH COMPANY, A CORPORATION OF CALIFORNIA

INDUCTANCE SYSTEM

Application filed June 11, 1928. Serial No. 284,606.

My invention relates broadly to inductance units and more specifically to inductance and coupling arrangements which are employed to cover a wide band of frequencies.

One of the objects of my invention is to provide an efficient inductance and coupling system for operation in connection with signaling apparatus generally, and more specifically to radio signaling systems.

Another object of my invention is to provide an efficient inductance system, that may be employed to cover a wide band of frequencies, contained in a unit as small and compact as is consistent with efficiency.

A further object of my invention is to provide an inductance unit which will cover a wide band of frequencies without the use of interchangeable coils and troublesome balancing of the circuits when interchangeable coils are employed.

A better understanding of my invention can be had by referring to the specification which follows and to the accompanying drawings, in which:

Figure 1 is a diagrammatic circuit arrangement illustrating the inductance units and their application to a space radio system; Fig. 2 illustrates a rear view of the inductance unit embodying my invention; Fig. 3 is an illustration of a cross-sectional view of the inductance unit of my invention shown partially in side elevation; Fig. 4 is a side elevation of the inductance unit of my invention; Fig. 5 illustrates the connections and relative inductance value at one adjustment of the inductance and coupling unit of my invention; Fig. 6 illustrates the same circuit with a lower inductance value obtained by the second adjustment of the inductance unit of my invention; Figs. 7, 8, 9 and 10 illustrate other values of inductance and circuit arrangements obtained by further adjustments of the inductance unit of my invention.

Referring to the drawings in detail the inductances are supported with respect to a panel structure 11 by means of pedestal members 19 extending perpendicular to the panel and carrying the frame structure for

the inductance. The frame structure comprises concentric tubular members 1 and 2, supported in grooves in the end plates 3 and 4 and secured therein by suitable screws 14. A pair of semi-circular conductor members in the form of sectors 5 are mounted on the interior of the insulated end plate 3 and are electrically connected as represented in Fig. 1 of the drawings. The opposite end plate 4 carries a set of contacts 25 extending interiorly of the inductance frame. The sectors 5 and the contacts 25 are electrically connected with the inductance windings 6, 7 and 8 as shown more clearly in Fig. 1. The panel structure 11 carrying a bearing 26 secured thereto by suitable screws 27 in which there is journaled the shaft member 28 rotatable by means of knob 16 from the front of the panel 29. Insulated sleeve 30 surrounds the projecting portion 70 of the shaft 28. The end of the shaft 28 is slotted as represented at 31 to receive the slotted end of the insulated shaft member 10 and provides a mechanical connection therewith without introducing capacity with respect to the inductance wirings. The insulated shaft member 10 projects through an aperture in the end of plate 4 and carries the switch structure shown at 9 and 15. The switch arms 9 engage the sectors 5 while the switch arms 15 engage the multiple contacts 25.

A resonating circuit which consists of a variable air condenser connected in parallel with a built-in stepped inductance system is shown in Fig. 1. This inductance value is controlled by a multi-position switch, the frequencies covered in the range of the variable condenser for each step corresponding to those secured with interchangeable receiver coils. The structure I employ for my inductance unit makes possible the selection of the required inductance values for the various steps without serious losses from unused turns at any frequency within a desired range. Figs. 2 and 3 show the structural arrangement of two fluted winding forms 1 and 2, one contained within the other, concentrically supported between two end plates 3 and 4 which carry the contacts 25

and sectors 5 of the switching mechanism. The outer form 1 carries, in addition to a coupling coil 6, a winding 7 tapped for steps 1 and 2 of the switching mechanism; the natural frequency of the dead end turns when step 2 is in use being considerably higher than the maximum frequency to which the circuit will resonate, hence no serious absorption occurs. The inner form 2 carries a winding 8 which is tapped to the switching mechanism for steps 3, 4, 5 and 6. Resonant absorption by coil 1 when working on steps 3, 4, 5 and 6 is prevented by its inclusion in the circuit as a shunt around the active turns of the inner coil as shown in Figs. 7, 8, 9 and 10. These combinations are automatically controlled by a double contacting laminated switch arm 9 mounted on an insulated shaft 10 inside the inner coil form 2. The active parts of the electrical circuit are thus insulated from the switch bearing clicker system 12 and other metallic parts of the control mechanism which are mounted on the sub-panel 11 of the unit, reducing the parasitic capacities to a low minimum. Coil windings 7 and 8 are wound on fluted forms 1 and 2 thus providing a low loss in the winding forms. The small contact of the form and winding as shown in Fig. 4 is adequate to hold the winding in position on the form.

Many advantages have been noted from the use of this inductance system as compared directly with separate coils for each frequency band. The stepped inductance and coupling unit when connected as the input circuit of a three element vacuum tube with the antenna coupling winding inserted in the plate circuit for tickler feed back produces oscillations over the greater part of the frequency range. It is to be understood that the inductance and coupling unit of my invention may be substituted for other type coils in both radio frequency amplifier and receiver circuits and in combination with equipment not referred to in this specification and that its application is therefore not limited to the circuit arrangement shown herein.

50. What I claim and desire to secure by Letters Patent of the United States is as follows:

1. An inductance and coupling unit comprising in combination a plurality of coil forms positioned one within the other, a plurality of coil windings positioned on said coil forms, end plates supporting said coil forms, a multi-contact switching mechanism supported between and by said end plates and contact members connected to said coil windings.

2. In an inductance and coupling unit a plurality of windings arranged on a plurality of cylindrical coil forms, said coil forms 65 concentrically supported between two end

plates, a switching mechanism supported between and by said end plates and within said coil forms, a plurality of contact members carried by said end plates, electrical connections between said contact members and said windings, means for adjusting said switching mechanism with respect to said contact members, and said electrical connection arranged with respect to said coil windings whereby said coil windings may be selectively connected in a plurality of multiple circuit arrangements by the adjustment of said switching mechanism.

3. In an inductance and coupling unit comprising in combination concentric tubular members having windings thereon, said tubular members supported by two end plates, one of said end plates having curved conductor members, the other of said end plates having contacts extended interiorly of said tubular members and electrically connected to the respective windings on said tubular members, a shaft extending through said end plates and having a contactor arm thereon, and said contactor adapted to simultaneously make contact with said contacts and conductor members.

4. In an inductance and coupling unit the combination of concentric tubular members having inductance windings thereon, said tubular member supported by two end plates, a pair of conductor members in the form of sectors mounted on the interior of one of said end plates, a set of contacts mounted on the other said end plate and extending interiorly of said tubular member, electrical connections between said windings and said contacts, a panel structure supporting said end plates and said tubular members and having a bearing therein, a shaft member extending through said bearing and through said end plates and having a contactor member mounted thereon and said contactor member providing an electrical connection between said conductor members and said contacts.

5. In an inductance and coupling unit the combination of concentric tubular members supported by end plates, contacts carried by one of said end plates said tubular members having windings thereon electrically connected to said contacts, a panel structure supporting said tubular members and said end plates, a bearing in one of said end plates and in said panel structure, an insulated shaft member extending through said bearings, a contactor member mounted on the portion of said shaft member extending through said tubular member, curved conductor members mounted on one of said end plates and means provided to rotate said shaft member whereby an electrical connection is provided between said contacts and said conductor members to provide a plurality of inductance values predetermined

by the electrical connections between said coil windings and said contacts.

6. In an inductance and coupling unit comprising a plurality of cylindrical coil forms arranged concentrically one within the other, a plurality of windings on said coil forms, a common support for said coil forms, a switching mechanism arranged on said common support, groups of contact members carried by said common support, a plurality of connections between each of said coil windings, groups of contact members and said switching mechanism, and external connections thereto whereby one of said coil windings, other of said coil windings, and a parallel connection of said coil windings may be selectively associated with an external circuit.
